UNITED STATES PATENT OFFICE

MATTI NIEMI, OF SEATTLE, WASHINGTON

AEROPLANE LAUNCHING DEVICE

Application filed August 24, 1931. Serial No. 559,023.

This invention relates to launching devices for aeroplanes, being an improvement over structure illustrated and described in my co-pending U. S. patent application, Serial No. 500,734 filed December 8, 1930.

Such prior invention consisting in apparatus allowing a plane to swing upwardly under its own power to a sufficient height above the ground to afford an acceleration of speed from an arc of descent, the present invention has for a primary object thereover, the provision of most efficient catapult mechanism adapted to impart an initial thrust to the released plane in accelerating the rise of momentum.

Another object resides in the provision of mechanism co-operative with the buoyancy developed by the plane's propeller for facilitating the upward swing activity of the same to its elevated disposition.

A further object is the provision of cushioned mechanism for locating the plane in an elevated disposition most efficient for obtaining the full effectiveness of the catapult thrust and at the same time allowing the plane to obtain a high development in the propeller speed prior to the release of such catapult structure.

A still further object consists in the provision of grappling devices accommodating a three-point suspension to the plane most advantageous in maintaining the same in a horizontal plane.

Further and more particular objects and advantages, together with the foregoing, should become apparent in the course of the following description and claims, the invention consisting in the novel construction, adaptation and combination of parts hereinafter described and claimed.

In the drawings—

Figure 1 is a longitudinal vertical section taken medially through apparatus representing a preferred embodiment of the present invention, a plane being indicated therewith in its elevated disposition prior to launching.

Fig. 2 is an enlarged fragmentary detail view of structure shown in Fig. 1.

Fig. 3 is a horizontal section taken on line 3—3 of Fig. 1; and

Fig. 4 is an enlarged vertical transverse section on the line 4—4 of Fig. 3, shown fragmentarily and with parts in side elevation.

Reference being had thereto, a suitable superstructure consists in upright front and rear girder members 6, 7 having their lower ends suitably embedded or otherwise secured to a base, and interconnected at upper extremities by longitudinal and transverse channels 8, 9, the girders being spaced sufficiently in excess of the wing spread of the plane as to readily receive the same.

In the present invention, utilizing grappling structure of the general character shown in my co-pending application, I attach, as by supporting brackets 10, 11 secured above the plane fusilage at opposite ends of the same, a pair of laterally spaced-apart bars 12 having longitudinally spaced transversely aligned apertures 13, selective of said aligned apertures receiving a transverse pintle 14 for engaging a pair of links 15. The opposite apertured ends of said links receive a pin 16 adapted for releasable engagement between the jaws 17 of a grappling hook 17. Said grappling hook and the manner of using the same is illustrated and described in detail in the aforesaid application, the present arrangement connecting the frame thereof, through a ring 19 and links 20, with a pair of cables 21 having their opposite ends secured with respect to the rear girder members of the superstructure as by means of eye-bolts or the like 22 attached to a horizontal cross rod 23.

A pair of cables such as 24, hereinafter termed elevating cables, are likewise connected to said hook frame 17, passing through fair leaders 25 and over pulleys 26 to respective weights 27 suspended adjacent the front girder members 6.

Said hook arrangement, having connection with selected apertures of the bars 12 slightly forwardly of the plane's weight center, is co-operable with a pair of cables 28 secured to the weights and adapted to pass through the ring 19, the terminal ends of said cables supporting a ring 30 adapted for engagement over a hook 31 secured to the rear portion of the bars 12 and serving as a balance support.

for the tail of the plane. 32 represents a control cable for elevating the weights 27 to drop the grappling hook into proximity of the ground, and 33 indicates a release cable passing through eyes 34, 35 and manually controlled by an operator, for spreading the jaws 17', said cable maintained taut through a suspended weight 36.

- As is believed evident, a plane in its disposition upon the ground is engaged by the jaws 17' and the ring 30, the pilot elevating the plane, with the cooperation of the weights, by means of the propeller energy in an arc about the axis of suspension of the cables 21. 10
- 15 A convenient adjustment, other than the separable weight blocks shown, in accommodating the weight of various types and characters of planes, might comprise a brake acting on the winch for the control cable 32. In 20
- restricting the height of elevation, cushion tires 37 supported by the forward cross channel 9 engage over the outer ends of the wings.

More particularly to the catapult devices, consisting in a pair of leaf springs 50 having 25 their inner ends attached to the aforesaid cross rod 23 and shouldering a rigid cross rod 39, the opposite ends engaging a thrust rod 51 supported for horizontal movement through means such as rollers 52 tracking between girder-supported companion rails 53, I provide medially of said thrust rod, a pulley member 54 tapering centrally from opposite edges and adapted for engagement within the throat portion of a thrust-receiving 30 bracket 55 secured adjacent the tail of the plane fusilage. As shown, such bracket affords an upstanding arm 56 for feeding the pulley into the throat. 57 represents control cables attached to the thrust rod for passage 35 over pulley wheels 58 to winches 59, said winches manually controlled for retracting the springs 50 to their inoperative rearmost position. A conventional pawl lock and 40 brake for the winch, the latter allowing extension of the springs to engage member 54 within the throat, are not shown.

The operation of the structure described is believed evident. The plane is elevated as 45 aforesaid into contact with the cushion tires, and the thrust rod advanced to engage the plane-secured bracket 55, subsequent to which engagement the pawl and brake are released from the winch drum. As the motor of the plane is accelerated to the desired propeller speed, the release cable 33 is actuated 50 by the operator upon the ground to release the grappling hook, the suppressed energy of the springs asserting a thrust to impart an accelerated speed to the released plane. Ring 55 60 30 slides over the hook as the plane moves forward.

The foregoing is believed clear. It is not my intention, however, to in any way confine myself except as limited by the scope of the hereto annexed claims, it being thought 65

readily within the ability of a mechanic or engineer to redesign the release structure for control by the plane's pilot, or to dispose the thrust-receiving bracket rearwardly of the plane rudder. Various further modifications 70 as might be desired are thought obvious.

What I claim, is,—

1. In aeroplane launching devices, the combination of means for elevating a plane, means to release the plane from its elevated 75 disposition, and means for imparting an initial thrust to the released plane to impel the same outwardly.

2. In aeroplane launching devices, the combination of means for supporting a plane in an elevated disposition, means for releasing the plane from its elevated disposition, and means for imparting an initial thrust to the released plane to impel the same outwardly. 80

3. In aeroplane launching devices, the combination of means for supporting a plane in an elevated disposition, means for releasing the plane from its elevated disposition, and means for accelerating the initial speed of 85 momentum of the released plane. 90

4. In aeroplane launching devices, in combination, means for elevating a plane about a constant axis, means for releasing the plane from its elevated disposition, and means for accelerating the initial speed of momentum 95 of the released plane.

5. In aeroplane launching devices, the combination with a plurality of cables, and means for attaching said cables to the plane at the front and to the rear, respectively, of the plane's weight center, said cables affording, 100 co-operative with the motive energy of the plane's propeller, an elevation of the plane about a constant axis, of means for releasing said plane from its elevated disposition, and means for accelerating the initial speed of 105 momentum of the released plane.

6. In aeroplane launching devices, the combination with a plurality of cables, and means for attaching said cables to the plane at the front and to the rear, respectively, of the plane's weight center, said cables affording, co-operative with the motive energy of the plane's propeller, an elevation of the plane, 110 of means for releasing said plane from its elevated disposition. 115

7. In aeroplane launching devices, a plurality of cables, means for attaching said cables to the plane at the front and rear of the plane's weight center and at opposite sides of a median line taken longitudinally of the same, means for elevating the plane, means for releasing the plane from its elevated disposition, and means for accelerating the initial speed of momentum of the released plane. 120

8. In aeroplane launching devices, a plurality of cables, means for attaching said cables to the plane at the front and rear of the plane's weight center and at opposite 125 sides of a median line taken longitudinally of the same, means for elevating the plane, means for releasing the plane from its elevated disposition, and means for accelerating the initial speed of momentum of the released plane. 130

sides of a median line taken longitudinally of the same, means for elevating the plane, and means for releasing the plane from its elevated disposition.

- 5 9. In aeroplane launching devices, a superstructure, cables suspended from the superstructure at the rear thereof, means for connecting the opposite ends of said attached cables to the plane, a pair of pulleys supported by the superstructure at the front thereof, cables passing over said pulleys, weights suspended by said last named cables at one end of the same, means for attaching the other ends of said weight-suspending cables to the plane, said weights co-operating with the motive energy of the plane's propeller for elevating the plane about the axis of suspension of said first named cables, and means to release the cables from the plane in 20 the elevated disposition of the latter.

10 10. The apparatus as defined in claim 9, and means supported by the superstructure for limiting the extent of elevation of the plane.

- 25 11. Aeroplane launching devices including a superstructure having means for suspending a plane in an elevated disposition, means for releasing the plane from said elevated disposition, and catapult devices for accelerating the speed of momentum of the released plane, said catapult devices comprising a horizontal transversely disposed bar adapted for engagement with the plane, rollers supported at opposite ends of said bar, 30 track-ways for said rollers for guiding said bar longitudinally of the superstructure, and spring means engaging said bar for impelling the same outwardly.

35 12. The apparatus as defined in claim 11 including control means for retracting or feeding said bar from or to the plane.

- 40 13. In aeroplane launching devices, a superstructure, cables suspended from said superstructure, means for attaching the opposite ends of said cables to the plane, said cables co-operating with the motive energy of the plane's propeller for elevating the plane about the axis of suspension of said cables, 45 means for limiting the extent of elevation of the plane, and means for releasing the plane from its elevated disposition.

50 14. In aeroplane launching devices, the combination with a superstructure, and means co-operating with the motive energy of the plane's propeller for elevating the plane in said superstructure, of cushion devices for limiting the extent of elevation of the plane in said superstructure.

- 55 15. In aeroplane launching devices, the combination with a superstructure including uprights spaced laterally in excess of the wing spread of the plane, a grappling hook adapted for engagement with the plane, cables secured to said grappling hook, said cables supported by the superstructure for

swing activity upwardly about a constant axis, devices for locating said plane in a predetermined elevated disposition responsive to swing activity of the same upwardly about said cable axis, and means for releasing said grappling hook, of catapult devices comprising a horizontally movable thrust rod adapted for engagement with the plane at the tail portion of the same, means for feeding or retracting said rod to or from engagement with the plane, and means responsive to a release of said grappling hook for impelling said rod outwardly to impart an accelerated speed of momentum to the released plane.

Signed at Seattle, Washington, this 20th day of July, 1931.
